D. D. SMITH.

DRAFT BEAM AND CONTINUOUS DRAW BAR FOR RAILWAY CARS.

APPLICATION FILED FEB. 17, 1917.

1,256,940.

Patented Feb. 19, 1918.

Fig. 1.

UNITED STATES PATENT OFFICE.

DAVID D. SMITH, OF OVERLAND PARK, MISSOURI, ASSIGNOR OF ONE-HALF TO JAMES EDGAR SMITH, OF NEW ORLEANS, LOUISIANA.

DRAFT-BEAM AND CONTINUOUS DRAW-BAR FOR RAILWAY-CARS.

1,256,940.

Specification of Letters Patent. Patented Feb. 19, 1918.

Application filed February 17, 1917. Serial No. 149,372.

To all whom it may concern:

Be it known that I, DAVID D. SMITH, a citizen of the United States, and a resident of Overland Park, in the county of St. Louis, 5 State of Missouri, have invented certain new and useful Improvements in Draft-Beams and Continuous Draw-Bars for Railway-Cars, of which the following is a specification containing a full, clear, and exact 10 description, reference being had to the accompanying drawings, forming a part hereof.

My invention relates to an improved draft and buffing apparatus for railway cars, and consists in the novel construction and arrangement of parts hereinafter described and particularly pointed out in the appended claims.

The object of my invention is to provide an improved continuous draft and buffing apparatus, which will be (preferably) made of cast-steel, and will connect the draw-bars at both ends of the car by a pair of channels (I-shaped in cross-section) set edgewise and extending from one draw-bar 25 to the other of each car, to take the draft strains of the entire train of cars; and which will have a separate continuous buffing-beam in the form of a pair of I-shaped metallic channels and cross-bars for connecting said 30 channels, extending from one end of each car to the other end of the same car, and inclosing and guiding said continuous draw-bar member, throughout the length of the latter; whereby each car of a train fitted with my invention will be "pushed" from the rear, and all draft strain will be transmitted throughout the train of cars so fitted by my improved continuous draw-bar, and all heavier buffing 35 throughout the train will be transmitted 40 throughout the train by my improved buffing-beam, there being a suitable yielding-connection between said continuous draw-bar (on each car) and its companion buffing-beam to permit a limited movement of said 45 continuous draw-bar with relation to its inclosing buffing-beam, prior to the succeeding heavier draft and buffing shocks and strains being imposed upon said buffing apparatus.

In the drawings, 50 Figure 1 is an inverted plan-view of my continuous draft and buffing apparatus.

Fig. 2 is a detail, longitudinal, vertical section of one end of same.

Fig. 3 is a vertical cross-section, taken on the line 3—3 of Fig. 1, with the parts enlarged, and 55

Fig. 4 is a detail cross-section taken through the continuous draw-bar on the line 4—4 of Fig. 2.

In the present instance, I have shown the 60 continuous draw-bar in the form of an integral casting, having two parallel channels 2 connected adjacent their ends by a top plate 3 and a bottom plate 4, and to which ends the usual couplers 5 are connected by a suit- 65 able bolt 6 or by any common means.

Said continuous draw-bar is located between, and inclosed on opposite sides by, the buffing and stiffening beam composed of a pair of parallel channels 7, which are connected by a series of cross-bars 8 and by the body-bolsters 9, all preferably cast integral, although it is evident that if it is desired to make the parts of separate wrought metal, or structural steel, such construction may be 75 followed, in both freight and passenger cars.

While the said buffing and stiffening beam may be called a "center" beam, yet it is absolutely a "draft-beam" and nothing else, for the reason that it is located below the plane 80 of the underframe of the car, and is not necessarily a part of said frame, although it may be readily cast integral with any of the patented cast-steel underframes now in use, as will be understood by those skilled in the 85 art.

Said body-bolsters 9 are formed with a recess 10 on their under side, in which (and through which) said continuous draw-bar is located and extends, the usual center-plate 11 90 being secured to the underside of said bolsters by means of bolts 12.

Said cross-bars 8 of said buffing and stiffening beam do not extend across the space between said parallel channels 7, beneath 95 said continuous draw-bar, so that by simply detaching and removing said center-plates 11 the said continuous draw-bar may be dropped and removed from its position between said channels 7, when required. 100

In other words, said cross-bars 8 are recessed upon their under edges, for the purpose of assembling and disassembling the apparatus, and the recess is provided, as described, in the underside of the body-bolsters 9, for the same purpose. 105

Vertically-alined long slots 14 are formed in the top 3 and bottom plates 4 of the said continuous draw-bar, for the passage of the usual center-pin, which is not shown.

A perforation 15 is also formed in the top of the said body-bolster 9, and in the center-plate 11, for the passage of the center-pin.

A plurality of horizontally-alined wide 10 slots, or openings, 16 are formed in the vertical webs of said continuous draw-bar, and pairs of combined draft and buffering followers 17 are mounted on edge in the said openings and extend transversely of said 15 draw-bar, with their ends projecting beyond the outer surface of said webs, in contact with the opposite cross-bars 8 of the said combined buffering and stiffening beam channels 7, which cross-bars act as abutments for 20 said followers, in transmitting the draft and buffering strains from said continuous draw-bar to the said beam channels, and through the latter the car is pushed and pulled, of course.

25 A combined draft and buffering spring, as 18, is located in the space between each pair of the said followers 17, so that the ends of said spring will bear against the opposite plates.

30 Common spring-plate lugs 19 are used to hold said springs in place upon said followers.

Some of said springs 18 are made heavier or stronger than others, as for instance, the 35 spring shown at the right-hand of Fig. 2 is lighter than the one shown at the left-hand of said figure, so that said heavier spring will not need to be compressed to any great degree in transmitting preliminary strains 40 of draft and buffering, while the lighter spring will act with its greatest power only when compressed to a greater extent than that required for said heavier spring to transmit the same strain. But said springs may be 45 all alike, if the builder desires them so.

I do not limit myself to the exact form and arrangement of parts shown in the drawing, as it is evident that many changes may be made by a skilled mechanic without 50 departing from the spirit or scope of my invention.

The operation is as follows:

In the construction shown, a pull on the coupler 5 causes its longitudinal movement, 55 together with the said continuous draw-bar, as well as the common coupler at the opposite end of said continuous draw-bar, and also a corresponding longitudinal movement of all the common couplers and continuous 60 draw-bars throughout all the cars of a train fitted with my invention.

With the movement of said continuous draw-bar all of the springs 18 will be compressed, and transmit the pull to the pulling 65 spring-plates 17, and thence to the pulling

cross-bars 8 of the center-beam, and thereby the car body, or car bodies of the entire train will be pulled.

In buffering, the action of the parts is very similar to that just described, all of said 70 springs 18 will be compressed by reason of the opposite movement of the said continuous draw-bar, and will transmit the buffering strains gradually, of course, to the buffering spring-plates, to the buffering cross-bars of 75 said center-beam, and through said beam the car body will be put into motion.

There will be little, or no, possibility of the continuous draw-bar being "pulled out" 80 and the consequent breaking - in - two of a train that is fitted with my invention, no matter how heavy the engine may be, and no matter if the train be one of the modern record-breaking "freights" of 100 cars, as the continuous draw-bar will extend 85 throughout the train, with each car having numerous connections with its continuous draw-bar, distributed practically throughout the length of said continuous draw-bar and the accompanying combined buffering and 90 stiffening center-beam, as will be readily apparent by an inspection of the drawing.

Although I have shown, in the drawing, but four pairs of cross-bars 8, distributed pretty well throughout the length of the 95 continuous center-beam's channels 7, yet it is obvious that additional pairs of cross-bars 8 may be supplied along the length of said center-beam, for the purpose of stiffening and guiding the said continuous draw-bar at additional points in its length.

100 I claim the following as my invention:

1. An improved draft and buffering apparatus for railway cars, consisting of a continuous draw-bar having a length approximating that of the car which is to carry it, and formed of a casting having integral top and bottom members which form hollow containers for draft and buffering springs and their followers; and a cast-metal center-beam open from end to end, and upon its 110 under side, and provided with suitable guides at intervals of its length, and arranged to inclose and guide said continuous draw-bar upon the top and opposite sides of the latter.

2. A cast-metal continuous draw-bar having a length approximating that of the car which is to carry it, and formed with a top and bottom which unite parallel vertical 120 sides and provide box-like structures for containing draft and buffering springs and followers; said box-like structures being slotted at opposite points to permit said followers to project beyond said structures; in 125 combination with a cast-metal center-beam which is of about the same length as said continuous draw-bar, and is open from end to end and upon its under side, and provided with integral cross-bars which are 130

gaged by the ends of said followers, and arranged to inclose and guide said continuous draw-bar upon the top and opposite sides of the latter.

5. 3. An improved draft and buffing apparatus for railway cars, consisting of a cast-metal continuous draw-bar having a length approximating that of the car which is to carry it, and having integral top and bottom members united by parallel members which are L-shaped in cross-section; a continuous center-beam open throughout its length and upon its under-side, and inclosing said continuous draw-bar upon the top and opposite sides of the latter; and means which yieldingly connect said draw-bar to said beam at various points in the length of both draw-bar and center-beam.

4. As a new article of manufacture, a cast-metal continuous draw-bar having two parallel sides which are of sufficient length to extend from end to end of a car, and a top and bottom which unite said parallel sides and form a box-like structure for containing the draft and buffing springs, and to which common draw-bars may be attached.

5. A cast-metal continuous draw-bar adapted to extend from end to end of a car, and having cast integral therewith top and bottom members which form hollow containers for the draft and buffing springs and spring-plates.

6. A cast-metal continuous draw-bar having a length approximating that of a car and having hollow end portions united by parallel members which are L-shaped in cross-section.

7. A cast-metal continuous draw-bar having hollow structures at points in its length; said hollow structures being slotted at opposite points, so that spring-seats may be located in the slots thus formed and project laterally from said continuous draw-bar at various points in the length of the latter, in combination with a center-beam having approximately the same length as that of said

continuous draw-bar, and having cross-bars which are engaged by the said projecting ends of said spring-seats, and suitable springs engaging said spring-seats, to yieldingly connect said continuous draw-bar to the said center-beam.

8. As a new article of manufacture, a cast-metal center-beam for railway-cars, comprising parallel members having integral cross-bars connecting the said parallel members at a plurality of points in the length of said members; the said cross-bars being cut away on the underside, to permit the placing and removal of a continuous draw-bar which is adapted to be located in the space between said parallel members.

9. As a new article of manufacture, a cast-metal draft-beam for railway cars, consisting of two parallel channels connected by cross-bars having recesses in their under edges, and all in the form of an integral casting having a clear opening throughout its length, and open upon its underside to permit the placing and removal of a continuous draw-bar which will occupy said clear opening.

10. As a new article of manufacture, a cast-metal draft-beam for railway cars, consisting of two parallel channels connected by cross-bars having recesses in their under edges, and all in the form of an integral casting having a clear continuous draw-bar opening formed in it from one of its ends to the other end, said opening being also devoid of a bottom, to permit the placing and removal from the bottom of the continuous draw-bar; and body-bolsters recessed upon their under-side and cast integral with said draft-beam.

In testimony whereof, I have signed my name to this specification, in the presence of two subscribing witnesses.

DAVID D. SMITH.
